UNITED STATES PATENT OFFICE

GARRETT L. NEWMAN, OF PHILADELPHIA, PENNSYLVANIA

AUTOMOBILE COAT TREE

Application filed November 2, 1926. Serial No. 145,750.

My invention relates to new and useful improvements in an automobile coat tree, and has for its primary object to provide an exceedingly simple and effective device that 5 may be mounted within an automobile for supporting one or more garments beneath a canopy to prevent the garments from becoming soiled from dust or rain which is often blown into the automobile during travel. 10 It is usually necessary in traveling in automobiles to pack wearing apparel in suit cases or small trunks, requiring that the garments be folded, so that they become creased or mussed, thus giving them a bedraggled appearance when worn unless pressed as soon 15 as unpacked. These disadvantages are entirely overcome by invention as the garments may be placed upon hangers, such as are generally used in the home, and a number of 20 these hangers then placed upon the tree and covered by a canopy that is preferably waterproof, thereby protecting the garments from the elements.

Another object of the invention is to so 25 construct the coat-tree that the majority of the parts may be dismantled and packed away when not in use, so as not to interfere with a person's occupancy of the automobile.

A further object of the invention is to construct 30 a canopy that will readily fit over the the garments placed upon the garment hangers when the latter are suspended on the tree.

A still further object of the invention is to provide simple and effective means for 35 preventing undesired rotation of the supporting element.

With these ends in view, this invention 40 consists in the details of construction and combination of elements hereinafter set forth and then specifically designated by the claim.

In order that those skilled in the art to 45 which this invention appertains, may understand how to make and use the same, I will 50 describe its construction in detail, referring by numerals to the accompanying drawings forming a part of this application, in which:

Fig. 1, is a front elevation of my improved 50 automobile coat tree with the canopy unbuttoned and the flaps thrown back.

Fig. 2, is a side elevation of the supporting member of the coat tree.

Fig. 3, is an end view of the nipple.

Fig. 4, is a side elevation thereof.

Fig. 5, is a perspective view of the canopy. 55

Fig. 6, is a plan view of the base.

Fig. 7, is a sectional view of the latter.

In carrying out my invention as herein embodied, 8 represents the base of the coat tree comprising a plate 9, preferably of disc shape having a plurality of holes 10 therethrough for the reception of fastening devices such as screws to secure the base to the upper surface of the floor of an automobile, while in the center of this plate is an internally screw threaded socket 11. 60

In the socket 11 of the bore is longitudinally mounted the nipple 12 having one end screw threaded, as at 13, for threaded connection with said socket, while the opposite end of the nipple is provided with oppositely disposed notches 14 to register with the projecting ends of the pin 15 mounted in the upright 16 some distance from its lower end. 70 The height at which the pin 15 is to be positioned is determined by the length of the nipple 12 into which the lower end of the upright projects. 75

The upright 16 forms a part of the support 17, and from the upright projects a bracket 80 arm 18, having a plurality of spaced notches in its upper surface, while the extreme outer end of said arm is bent upward to form a finger 20 which acts as a stop, as will be later described, and in the region of the connection between the upright and bracket arm, or at the end of said bracket arm opposite the finger 20 is mounted a pin 21, which also acts as a stop. 85

On the bracket arm 18 are mounted one or 90 more garment hangers 22, of any desirable or well known construction including a hook 23 which directly engages the bracket arm, and preferably rests in one of the notches 19, but in case the hook should become disengaged from its notch, the hanger will be prevented from displacement from the bracket arm by the stops 20 and 21. 95

The numeral 24 denotes a canopy of suitable, flexible material, and is preferably con- 100

structed from water-proof material, such as rubberized fabric or the like. The canopy is fashioned to provide shoulder strips 25, the edges of which diverge from their upper toward their lower ends but said upper ends are unattached to each other so that the canopy may be passed about the upright 16 of the support 17, and the hooks of the hanger or hangers which may be suspended from the bracket arm. From the shoulder strips depend the end walls 26, the edges of which also diverge from their upper toward their lower ends, and to the rear edges of the shoulder strips and end walls is secured a rear or back wall 26, the upper end of which tapers toward its vertical center line, while to the front edges of the shoulder strips and end walls are secured the front flaps 28, preferably arranged to meet and overlap along the vertical center line of the canopy, and said flaps may be provided with the complementary parts 29 of snap fasteners, hooks and eyes, or some equivalent securing means, such as buttons and button holes 16. After the canopy has been placed in position the flaps may be fastened together thereby excluding dust, rain, snow and the like from garments within or under the canopy.

The construction and arrangement of the parts of the canopy are such that it is flared out both to the front and rear toward the bottom thereof.

In practice, the base 8 is fastened to the floor of an automobile directly behind a seat 35 in such manner that when the nipple 12 is secured into the base socket 11, the notches 14 are longitudinally of the automobile, although they could be in some other position if desired.

40 When the device is not in use, the support 17 and the nipple 12 are removed and may be placed under the seat or any other convenient place, and the canopy may be folded up and stored until its use is desired.

45 When the device is to be used, the nipple 12 is screwed into the base socket 11, and when the support is brought to the automobile, it is only necessary to insert the lower end of its upright in the nipple 12 and turn the support until the ends of the pin 15 register with the notches 14, at which time the bracket arm 18 should be projecting rearwardly so that the suspended garments will be within the space between the back of the forward seat, in that space usually occupied by the feet of riders.

55 It is to be understood that the support 17 may be carried into a building, and the garment hangers with garments thereon placed upon the bracket arm, and the canopy then placed about all the garments on the support.

60 While I have described my invention with particular relation to its use for tourists, it is to be understood that a number of the trees 65 may be placed in a delivery automobile, and

the garments hung thereon for delivery to customers.

Of course I do not wish to be limited to the exact details of construction as herein shown as these may be varied within the limits of the appended claim without departing from the spirit of my invention.

Having thus fully described my invention, what I claim as new and useful is:

A device of the kind described comprising a support including an upright, a horizontal arm projecting only to one side of said upright at its upper end, said arm having notches at the top portion thereof, a vertical finger projecting upwardly from the outer end of the arm to act as a stop and a pin projecting upwardly from said arm adjacent the point of its connection with upright, said pin also acting as a stop, clothes hangers having portions engaging the horizontal arm and registering with the notches for spacing said clothes hangers, said clothes hangers being prevented from becoming accidentally displaced from the arm by the stops and a canopy supported by the horizontal arm and co-acting with the clothes hangers whereby the latter will hold said canopy in a distended condition.

In testimony whereof, I have hereunto affixed my signature.
